4 Claims

ABSTRACT OF THE DISCLOSURE

The disclosure is of a mold for assembling an electron tube comprising a first disk having a rectangular aperture adapted to receive an apertured container carrying a quantity of powdered glass. A two-part cylindrical member is seated on the first disk and has a plurality of transverse slots, with half of each slot being in one part and the other half being in the other part. The slots in the two-part member are adapted to receive cathode electrodes which have upper leads and lower leads, with the cathodes inverted so that the upper leads penetrate through the apertures in the glass container and are embedded within the powdered glass. An apertured shield member and then a second disk of glass or the like, which is to comprise the stem in the completed tube and having rows of apertures, are seated on the two-part member, with the lower leads of said cathodes each extending through aligned apertures in the shield and in the glass disk. A solid cylindrical member having rows of holes extending through its length is seated on the second disk with its holes aligned with the apertures in the disk so that the lower cathode leads can extend through the second disk into the holes in the cylindrical member.

A hollow open-ended tube encloses all of the above-mentioned parts, and a relatively heavy member which serves as a weight caps the entire assembly.

The entire assembly is suitably heated to melt the powdered glass and the second disk, and, when the assembly is cooled, a bond is formed between the glass and the upper and lower cathode leads, and a completed cathode assembly is provided. This cathode assembly can then be readily made into a completed tube.

BACKGROUND OF THE INVENTION

The principles of the invention relate particularly to display tubes which include a stack of filamentary cathode electrodes in the form of numerals, letters, or the like mounted in a gas-filled envelope in conjunction with an anode electrode. Usually, the cathode electrodes are supported by mounting tabs on two support posts which are secured to the anode. For the most part, the cathode assembly in tubes of this type is made by hand, a time-consuming operation with the above arrangement and one which provides cathode support which is adequate but open to improvement.

SUMMARY OF THE INVENTION

The present invention provides an improved arrangement for assembling the cathode stack in a display tube and imparting optimum strength and rigidity to the stack. The apparatus of the invention comprises a mold which includes a plurality of parts and which is adapted to contain a carrier for powdered glass into which one set of cathode tabs is to be sealed, a slotted structure for supporting the cathodes themselves, and a glass disk which receives the cathode leads and becomes the stem of the final tube envelope. The entire assembly of mold and cathodes is heated to soften the powdered glass and the glass disk

2

to form, on cooling, an intimate bond with the cathode tabs and leads.

DESCRIPTION OF THE DRAWING

In the drawing:

FIG. 1 is a perspective view of a type of electrode assembly made by means of the mold of the invention;

FIG. 2 is an exploded view of the mold of the invention; and

FIG. 3 is a side elevational view, partly in section, of the mold of the invention as it appears when assembled.

DESCRIPTION OF THE PREFERRED EMBODIMENT

The apparatus of the invention is particularly suited for making an electrode assembly 10 of the type shown in FIG. 1. Such an assembly is used in a multiple cathode indicator tube and includes a glass stem 20 on which is seated a metallic lower shield 30 which has the form of an elongated container and is held in place by a mica disk 40. The assembly also includes a similar elongated upper metallic shield 50 which contains a glass block 60 in which the upper tabs 70 of cathode electrodes 80 are embedded. The upper shield includes suitable apertures through which the tabs 70 extend without touching the shield. The cathode electrodes 80 also have lower cathode tabs 90 which extend through suitable apertures in the lower shield to the interior of the lower shield member where they are welded to tube pins 100. The tube pins extend through the stem to which they are secured.

The apparatus of the invention comprises a mold 102 which is shown exploded in FIG. 2. All parts of the mold are made of carbon or other suitable materials which do not adhere to molten glass. The mold includes a relatively large disk 120 which includes a central aperture 130 in which is seated a disk 140 having a rectangular aperture 150. The rectangular apertured is adapted to receive the upper shield 50 of the tube assembly 10. The shield is inserted with its apertured surface facing up and containing a quantity of powdered glass.

Next in order, the mold includes a split cylinder 160 comprising two identical halves 170 and 180 which have mating transverse slots 190. The slots are adapted to receive the cathode electrodes 80 positioned upside down and with their upper tabs 70 inserted into the powdered glass in the upper shield. The cathodes have the tube pins or leads 100 welded to their lower tabs 90 at this time. The two-part member is designed so that the character portion of each cathode is contained within the slots and reaches to about the upper end of the slots. The two-part cylinder 160 includes a generally flat upper surface 200 surrounded by a retaining wall 210. The mica disk 40, to which the lower shield 30 is secured by suitable tabs, is threaded on the tube pins and lower cathodes tabs and is set in place on the upper end of the two-part member with the shield down and the mica disk up. Next, the stem disk 20 having suitable apertures is threaded on the tube pins and is seated on the mica disk. A relatively large cylindrical piece 220 having apertures 230 for receiving the tube pins 100 is then threaded on the tube pins and is seated on the stem disk 20. An enclosing cylinder 240 is provided for enclosing all of the above-described parts, with its lower end inserted in the opening 130 in the lower disk 120 and with its upper end positioned just below the upper end of cylinder 230 to provide a seat for a relatively heavy disk 250 which has a central depression which receives the upper end of cylinder 230. The disk 250 operates as a weight to hold the parts in compression.

The mold 102, with the parts of the tube assembly 10 included as described above, can be formed into a rigid unitary assembly by passing the mold through a suitable

oven which provides sufficient heat to melt the powdered glass in the upper shield and the stem disk 20. The oven atmosphere is preferably inert to prevent oxidation of cathode elements. When the assembly of mold and tube parts is cooled, the softened glass solidifies to form a rigid unitary structure. Of course, it is clear that the desired heating can be effected in other ways, for example, by means of radiant energy.

What is claimed is:

1. A mold for assembling a portion of an electron tube comprising:
  - a plate having a rectangular aperture adapted to receive a shield means and a quantity of powdered glass in which electrode leads are to be secured,
  - a two-part cylindrical member having a plurality of transverse slots with the slots made up of a portion in one part and a portion in the other part, said slots being adapted to receive cathode electrodes which have upper leads and lower leads, with the cathodes being inverted so that the upper leads penetrate into said quantity of powdered glass,
  - an insulating disk which is to comprise the stem in the completed tube having rows of apertures and seated on said two-part cylinder, with the lower leads of said cathodes each extending through one aperture therein,
  - a cylindrical member having rows of apertures corresponding to said rows of apertures in said disk positioned on said disk with said lower cathode leads inserted in its apertures,
  - a hollow open-ended tubular member enclosing all of said parts and terminating just below the upper end of said last-mentioned tube, and
  - a relatively heavy member seated on said tube and on said hollow cylinder.
2. A mold for assembling a portion of an electron tube comprising:
  - a plate having a rectangular aperture adapted to receive a container carrying a quantity of powdered glass,
  - a two-part cylindrical member having a plurality of

transverse slots with the slots made up of a portion in one part and a portion in the other part, said slots being adapted to receive cathode electrodes which have upper leads and lower leads, with the cathodes being inverted so that the upper leads penetrate through holes in said glass carrier and terminate within the powdered glass,

an insulating disk which is to comprise the stem in the completed tube having rows of apertures and seated on said two-part cylinder, with the lower leads of said cathodes each extending through one aperture therein,

a cylindrical member having rows of apertures corresponding to said rows of apertures in said disk positioned on said disk with said lower cathode leads inserted in its apertures,

a hollow open-ended tubular member enclosing all of said parts and terminating just below the upper end of said last-mentioned tube, and

a relatively heavy member seated on said tube and on said hollow cylinder.

3. The mold defined in claim 1 wherein all of said parts, except those made of glass or an insulating material, are made of a heat-conductive material to which molten glass does not adhere.

4. The mold defined in claim 1 wherein all of said parts, except those made of glass or an insulating material, are made of carbon.
